UNITED STATES PATENT OFFICE.

JEREMIAH W. STALLINGS, OF LAFAYETTE, ALABAMA.

PLOW.

953,867.

Specification of Letters Patent.

Patented Apr. 5, 1910.

Application filed April 15, 1909. Serial No. 490,088.

To all whom it may concern:

Be it known that I, JEREMIAH W. STALLINGS, a citizen of the United States, residing at Lafayette, in the county of Chambers 5 and State of Alabama, have invented certain new and useful Improvements in Plows, of which the following is a specification.

My invention relates to plows, and more particularly to the blades thereof, and my 10 object is to provide a sweep of the type commonly known as wing sweeps, of a novel and highly useful construction to turn the soil and adjust the width thereof, in addition to a point, for instance a scooter, the 15 purpose of which will be hereinafter described.

In the accompanying drawings, which illustrate my invention, and form a part of this specification, Figure 1 is a perspective 20 view of my improved device. Fig. 2 is a horizontal cross section through the standard looking down upon the share. Fig. 3 is a central vertical section through the blades and that portion of the standard shown in 25 Fig. 2, and, Fig. 4 is a rear elevation of the wings removed.

In the practical embodiment of my invention, I provide in connection with a single 30 foot or supporting standard α , comprising parallel side arms α' , and formed by intermediately bending a single bar of metal, the upper free ends of said bar being suitably secured to the beam A' of a plow A , a wing sweep comprising similar shaped wings 5, 35 extending upwardly in rearwardly diverging planes, and curved intermediate their ends sufficiently to produce a spiral movement of the soil for pulverizing the same. The wings 5 have lateral extensions 6 upon their con-

tiguous ends and adjacent their lower ends, 40 which extensions are adapted to overlap one another and are provided with elongated slotted openings 7 through which the heel bolt 8, extending between the standard side arms α' passes. Thus wings 5 may be adjusted toward and away from one another 45 when desired.

The plow point or scooter 9, through which the heel bolt 8 also passes, is in accordance with my invention, made of sufficient 50 width to span and cover the slots 7 in any adjusted position of wings 5, to prevent the collection of trash.

Having fully described my invention, I claim:

The combination with a standard, of a wing-sweep arranged thereon, comprising separate curved wings provided with laterally extending and normally horizontally arranged projections, said projections being 60 arranged upon the forward side of said standard in superposed relation, said projections being provided with relatively long straight registering slots which normally lie in a horizontal plane, whereby said wings 65 may be adjusted laterally without changing the angles of the same, a headed bolt passed through said slots and said standard, a clamping nut arranged upon said bolt, and a plow point arranged upon the forward 70 side of said projections, overlapping the same, and clamped in position by said bolt.

In testimony whereof I affix my signature in presence of two witnesses.

JEREMIAH W. STALLINGS.

UNITED STATES PATENT OFFICE.

VLADIMIR TCHEREPANOFF, OF GATCHINA, RUSSIA.

COMBINED EXPLOSION AND STEAM MOTOR.

953,868.

Specification of Letters Patent. Patented Apr. 5, 1910.

Application filed July 18, 1908. Serial No. 444,240.

To all whom it may concern:

Be it known that I, VLADIMIR TCHEREPANOFF, a subject of the Emperor of Russia, and a resident of Gatchina, Russia, 5 (my post-office address being Gatchina, Lutzev street 54,) have invented certain new and useful Improvements in or Relating to Combined Explosion and Steam Motors, of which the following is a specification.

This invention relates to a rotary motor operated by means of explosion cylinders having reciprocating pistons.

A practical construction according to this 15 invention in which the motor is combined with a vapor turbine is illustrated by way of example in the accompanying drawings in which—

Figure 1 is a vertical section through the 20 axis of the crank shaft of the upper cylinder. Fig. 2 is a section in a plane perpendicular to that of Fig. 1. Figs. 3 and 4 are detail views on an enlarged scale. Fig. 5 is a detail view showing the high portion of 25 the cam y^3 in operative relation with the pumps.

The letters a^1 a^2 a^3 a^4 a^5 indicate the frame of the machine. At both sides of the frame are secured the ends of a jointed crank shaft 30 h^3 h^4 . If it is desired to make the motor vertical, the shaft could be suspended directly by means of the lugs a^6 . The motor will then act as a gyroscope at the same time.

B^1 B^2 B^3 B^4 (Fig. 2) are the driving cylinders of the engine.

c^1 c^2 c^3 c^4 are pumps for supplying liquid fuel, d^1 is a turbine wheel, e^1 a fan, f^1 a switch intended to govern the electric current to the sparking plugs, v^1 a hand wheel 40 for regulating the length of the radius of the circumference described by the crank for the purpose of regulating the length of stroke of the pistons, g^1 is the conduit for the escape of the products of combustion, 45 b^5 b^6 b^7 b^8 are steam jackets.

The motor can be constituted by two, four or more curved cylinders secured between two disks h^1 h^2 (Fig. 1) which can rotate with the cylinders about the fixed crank shaft, the ends h^5 h^6 of which are secured to the frame a^1 a^5 . The sockets or hubs h^5 h^6 of the disks are carried by two bearings 50 a^3 a^4 .

The four rotary cylinders B^1 B^2 B^3 B^4 curved in the shape of an arc of circle, are

provided respectively with pistons b^1 b^2 b^3 b^4 provided with packing at their ends, to form tight joints. The said pistons are connected together in couples by rods 3^9 3^{10} passing through longitudinal slots s in the 50 cylinders and intersecting each other at a point o^3 coinciding with the axis of the whole device. Their sockets q^1 q^2 q^3 q^4 are connected by a spider o^2 to the adjustable ball bearing o of the crank of the fixed shaft. 55 The said spider forms a connecting rod for transforming the reciprocating movement of the pistons along the cylinders, into a continuous rotary motion. In the construction described, as the shaft is fixed, the four 70 cylinders will rotate about its axis o^2 . This rotary movement will continue until the alternative explosions of the mixture in the end of the cylinders cease. The explosions take place in the following manner. The 75 liquid hydrocarbon is introduced from a tank arranged outside the zone of rotation of the motor through a conduit n to the liquid fuel pumps c^1 — c^4 which discharge it into the vaporizers m^1 m^2 m^3 m^4 . In order 80 to insure complete evaporation of the liquid, each vaporizer is provided with two chambers; one of which is provided with a series of metal nettings p^1 . (Fig. 3.) The other chamber m^3 of the vaporizer is intended to 85 receive compressed air which is admitted into it toward the end of the piston stroke by a valve r communicating with the cylinder. During the return stroke of the piston, the said compressed air is drawn through the 90 nettings p^1 and returns into the cylinder carrying with it the liquid which it atomizes and volatilizes in the space provided with the nettings. The said mixture of air and vapors passes into the cylinder through 95 small holes made in the cover of the cylinder, where the mixture is ignited by the 100 sparking plug h^1 . When the piston arrives at the bottom of its stroke, it uncovers the exhaust ports s^1 s^2 s^3 s^4 and the inlet ports s^5 s^6 s^7 , through which the air discharged by 105 the fan e^1 passes into the cylinder in order to expel therefrom the combustion products. The fan e^1 is mounted loosely on the main fixed shaft and receives a rotary movement 110 accelerated relatively to the number of revolutions of the motor, by means of a toothed wheel gear t^1 t^2 t^3 t^4 , the first wheel t^1 of which is secured to the hub of the fan, and the last wheel t^4 is keyed to the shaft. The 110
